UNITED STATES PATENT OFFICE

EMIL JAGENBERG, OF DUSSELDORF, GERMANY.

MACHINE FOR MAKING BOXES.

1,102,755.

Specification of Letters Patent.

Patented July 7, 1914.

Application filed March 10, 1914. Serial No. 823,673.

To all whom it may concern:

Be it known that I, EMIL JAGENBERG, a subject of the German Emperor, and resident of 107 Himmelgeisterstrasse, Dusseldorf, Germany, manufacturer, have invented certain new and useful Improvements in and Relating to Machines for Making Boxes, of which the following is a statement.

The present invention relates to an improvement in such machines, as have been described in the United States specification 1,021,315.

In particular, the present invention relates to an arrangement for pushing the boxes from the forming plates fitted to an endless belt conveyer.

With the known arrangements for pushing off the boxes, this operation must be effected comparatively quickly. Furthermore the pushers do not act exactly longitudinally to the forming plates. The consequence is, that the edges of the boxes, which fit rather tightly on the forming plates are injured while being pushed off.

The object of the present invention is to avoid this trouble by the boxes being pushed off by aid of lugs traveling continuously in the same direction but at a higher speed than the forming plates around the same axis. Thereby a very slow and smooth push is obtained as the travel of the forming plates during such pushing off operation is very long, and it is no more necessary for the arms carrying the pusher lugs to return into an initial position. The lugs are, furthermore, during the pushing off operation, swung to a certain degree toward outside, at the same rate as the boxes move toward outside in sliding off. Therefore the pusher lugs act exactly longitudinally to the forming plates, whereby all hitching and choking of the boxes is avoided.

In the accompanying drawing Figure 1 is a longitudinal section, Fig. 2 a plan of the arrangement.

The wheel 18 on which the endless band 16 with the forming plates lies is driven by means of chain *a* in the direction indicated by the arrow. The shaft *d* of this wheel 50 drives by means of a pair of gears *b* a shaft *f* with an angular velocity which is one and a half times as great. This shaft *f* again drives by means of a pair of gears *g* two pairs of arms *h* fitted loosely revoluble on the shaft *d*, which arms are coupled to the gears *g* next to them. The arms *h* are ar-

ranged at both sides of the band 16, and each of them has hinged to its end a rocking lever *i*, in which a bolt *l* with a lug or gripper *k* is slidably and revolubly fitted 60 at the end turned toward the band. This lug *k* is under action of a spring, which tends to slightly press it toward the inside. Through slots *m* in the said arms *h* pins *n* of the rocking levers *i* project, whereby the 65 stroke of the latter is limited, and springs *o* tend to draw the rocking levers *i* toward the shaft *d*.

The forming plates or cones 23 are arranged at a pitch on the band 16 corresponding to one third of the circumference of wheel 18. The arms *h* arranged at either side of the band are arranged opposite to each other in the same direction. After the wheel 18 has completed one third of a revolution, not only the following forming plate will have reached the position of the preceding one, but also the second arm *h* will have reached the position of the preceding one, as owing to the gearing by the 70 gears *b* the arms travel faster than the wheel 18, namely making one half revolution. The arms *h* are so arranged, that the lugs *k* will always reach the highest point of wheel 18 simultaneously with a forming 75 plate, whereupon from this point they gradually lead ahead of the forming plate. When, thus, the lugs have at both sides met up against the edges of the box *s* on the respective forming plate, the box will be 80 slowly pushed off the forming plate. The lugs first meet against bevel surfaces *t* of the forming plates, whereby they are pushed apart, and then bear safely and steadily 85 against the edges of the box, adapting themselves to the incline of the latter by being pivotable. The forming plates are, however, as is well known, tangential to the periphery of the wheel 18. Therefore the box, while being pushed off the forming plate, 90 will not travel in a circular line but through a flatter curve, to which also the path of the lugs *k* must be adapted, if they are not to catch or choke during the operation and thereby injure the edges of the box. For 95 this purpose the rocking levers *i* are provided, to which the rollers *p* are fitted, which ride during the pushing off operation on suitably shaped cams *r*, so that the lugs *k* are moved outward at the same rate as the 100 box. During the pushing off operation the lugs travel exactly longitudinally to the 105

110

forming plate, so that the box is pushed off smoothly and without any hitch.

The forming plates may, of course, also be arranged at any other pitch than one third of the periphery of wheel 18. Only then the velocity of the arms h , which may be provided of any number, must be accordingly rated, so that one pair of lugs will always reach the highest point of the wheel 18 approximately at the same time as a forming plate.

I claim:

1. A device of the character described, comprising a rotatable wheel, a carrier band engaging the same; cores movably mounted on the band, arms rotatably arranged at both sides of the wheel, means for imparting to said arms a higher speed than the band-

speed, levers pivoted to the arms, grippers pivoted to the levers and adapted to engage 20 the boxes carried by the cores, and means for rocking said levers outwardly.

2. A device of the character described comprising a rotatable wheel, a carrier band 25 engaging the same, cores mounted on the band and having beveled faces, arms rotatably arranged at both sides of the wheel, means for imparting to said arms a higher speed than the band-speed, levers pivoted to the arms, and grippers revolvably and slidably secured to the levers and adapted to 30 engage the beveled core-faces.
